UNITED STATES PATENT OFFICE

2,481,741

SAFETY SLEEPER FOR BABIES

Sherburne R. Graves, Plymouth, N. H.

Application January 17, 1945, Serial No. 573,260

3 Claims. (Cl. 128—134)

1

This invention relates to sleeping bags designed particularly, though not exclusively, for infants.

Numerous sleeping bags have in the past been designed with a view toward safely keeping infants in their cribs and preventing them from getting from under, or kicking off, their covers. However, many of these prior sleeping bags, being relatively tight about an infant to check its movements, also restrict or hinder the natural turning and kicking motions of the reposing infant, with the result that the infant feels uncomfortable and becomes irritable when placed in the bag. Other sleeping bags which are sufficiently loose about an infant to give it some freedom to turn about and kick with its feet do not always prevent the disarray of the covers when the infant turns or kicks. In either case the infant is burdened down not only with the sleeping bag but with all the covers as well, thus not only causing further discomfort to the infant but seriously interfering with the natural growth and development of the infant's body and particularly of its feet.

It is the object of the present invention to provide a sleeping bag, particularly for infants, which has none of the disadvantages of the prior sleeping bags, that is to say, which neither restricts the natural turning and kicking activities of a reposing infant, nor permits any disarray of the covers in consequence of the infant's turning and kicking, nor lies heavily upon the infant even when extra covers are used on top of the bag.

The nature and objects of the invention will best be understood from the following description of an illustrative embodiment thereof shown in the accompanying drawings, in which:

Fig. 1 perspective illustrates the use of a sleeping bag which embodies my invention.

Fig. 2 shows a garment for an infant which is advantageously used in connection with the sleeping bag.

Fig. 3 is a perspective view of the sleeping bag alone.

Fig. 4 is an end view of the sleeping bag.

Fig. 5 illustrates a detachable element of the sleeping bag.

Referring to the drawing, and particularly to Fig. 1, the reference numeral 10 designates a conventional bed or crib having a frame 11 for supporting a mattress 12, and upright slats 13 of a suitable railing. Preferably attached to the mattress 12, in a manner hereinafter described,

is a sleeping bag 14 which embodies the present invention.

The sleeping bag 14, which may be made from any suitable textile fabric and formed by sewing together any suitable number of separate pieces, has a back 15, a bottom 16, sides 17, and a cover 18 consisting of two separate pieces 19 which may be joined or separated by the slide 20 of a conventional slide fastener having the usual track 21. The sleeping bag 14, or at least the back 15 thereof, is preferably rubber-lined internally as at 22. The sides 17 of the bag are of progressively increasing breadth toward the bottom 16 thereof and the latter is also of considerable breadth so as to make the bag more voluminous at the bottom than at the top. As best shown in Figs. 3 and 4, a flap 23 is sewed at 24 to the bottom 16 of the bag to form therewith a pocket 25 which is open at 25a for the insertion of a board 26 (Fig. 5). The board 26 may be made of wood or any other suitable material which is fairly stiff so as not to collapse in the pocket 25 (Fig. 1) even when some covers (not shown) are placed over the sleeping bag. Snap fasteners 27 may be employed to close the pocket 25 after the insertion of the board 26 thereto.

Transverse straps or belts 30 and 31 are provided for attaching the sleeping bag 14 to the crib 10, and preferably to the mattress 12. The strap 30 is suitably held or secured to the head end of the back 15 and passed around the mattress 12 in the fashion shown in Fig. 1. The strap 30 is passed through a pocket on the back 35 of sheet 15. The other strap 31 is received in a sleeve 32 which is sewed at 33 to the flap 23, and is then passed around the mattress as shown in Fig. 1.

The board 26, which preferably fits snugly in the pocket 25, is kept erect therein when the back 15 of the sleeping bag is flat on the mattress 12 and the straps 30 and 31 are attached to the latter. This is due to the sleeve 32 which, by virtue of its attachment to the end flap 23 intermediate the upper and lower edges thereof, resists any inward collapse of the board-holding pocket 25.

The infant, when placed in the sleeping bag on the mattress, has full freedom to move its feet and toes due to the erect disposition of the bottom of the bag, yet is securely held against unchecked rolling on the mattress within the narrower confines of the bag at the head end 35 thereof. The infant will also receive the full

benefit of any covers placed over the bag without being burdened with their full weight.

To prevent the infant from crawling from the sleeping bag and from under covers placed thereon, the infant is preferably clothed in a garment 40 of the type shown in Fig. 2, comprising a sack-like body piece 41 closed at the bottom and provided with sleeves 42 and a slide fastener 43 down the back. Attached to the bottom of the sack 41 is a tab 44 with a ring 45, adapted to receive a spring-closed hook 46 which is swivelly joined at 47 with a strap 48 to be slung around one of the slats 13 of the crib as shown in Fig. 1. The tab 44 and ring 45 are passed through suitable openings 50 and 50' in the board 26 and the pocket 25 of the sleeping bag respectively. When the infant in the garment 40 is thus strapped to one of the slats 13, it cannot crawl from the sleeping bag 14, yet may turn to its heart's content due to the swivel connection between the hook 46 and the strap 48. To remove the infant from the sleeping bag, it is merely necessary to remove the spring-closed hook 46 from the ring 45 on the tab 44 and to open the slide fastener 21 of the sleeping bag, as will be readily understood.

Attached to the back 15 of the sleeping bag 14, preferably by means of snap fasteners 52, is a head rest 54 upon which the infant may drool or vomit without dirtying the sleeping bag. The head rest 54 may from time to time be detached from the sleeping bag for washing.

It is to be understood that the sleeping bag 14 may be used with all its advantages with or without the head rest 54 and with or without the garment 40 and its detachable strap 48.

I claim:

1. A collapsible sleeping bag having, in combination, a closed foot end, a pocket formed on said foot end adapted to hold a stiff reinforcing member, and a laterally extending sleeve on the outside wall of said pocket adapted to receive a securing strap, a lateral edge of said sleeve being secured to said pocket wall above the lower edge thereof.

2. A collapsible sleeping bag having, in combination, a closed foot end, a pocket that is substantially coextensive with said foot end, a stiff

member in said pocket substantially coextensive therewith, and an external sleeve secured to said pocket intermediate the upper and lower margins thereof adapted to receive a securing strap transversely disposed to the foot of said bag.

3. A collapsible sleeping bag having, in combination, a base sheet, a top covering portion, a closed foot end, a pocket formed at said foot end substantially coextensive therewith, a stiff reinforcing member in said pocket, a wide sleeve having one lateral margin thereof secured to the outer wall of said pocket intermediate the upper and lower edges thereof and a free lateral margin spaced therefrom, a securing strap for the head end of said base sheet, and a securing strap passing through said sleeve, said straps being adapted to maintain said bag under sufficient tension to hold said pocket and said stiff member substantially upright during use.

SHERBURNE R. GRAVES.
